UNITED STATES PATENT OFFICE.

DAVID B. SMITH, OF CAPE GIRARDEAU, MISSOURI.

HOLDER FOR PORTABLE FIRE-EXTINGUISHERS.

1,297,024.

Specification of Letters Patent. Patented Mar. 11, 1919.

Application filed October 28, 1918. Serial No. 260,049.

To all whom it may concern:

Be it known that I, DAVID B. SMITH, a citizen of the United States, residing in the city of Cape Girardeau, county of Cape 5 Girardeau, and State of Missouri, have invented new and useful Improvements in Holders for Portable Fire-Extinguishers, of which the following is a specification.

This invention relates to fire extinguishers 10 and more particularly to those of the hand type and utilizing a chemical extinguishing agent. It is intended more particularly for use on automotive conveyances such as automobiles, tractors, motorboats, aeroplanes, 15 and the like, and has for its principal objects to detachably support the extinguisher in convenient reach of the driver and to provide for its operation while so supported and the distribution of the extinguishing agent to a place remote from the 20 support, whereby to minimize the fire risk and to facilitate quick and efficient action in combating a fire occurring in a place ordinarily inconvenient of access. Other objects 25 and advantages to be attained will herein-after more fully appear.

The invention consists essentially in a novel supporting device in which the extinguisher is held thereon with sufficient 30 stability to withstand the usual jarring and jolting motions to which it is subjected on the vehicle, and yet may be quickly removed therefrom should occasion require; said supporting device having a pipe connection 35 with which the nozzle or outlet of the extinguisher has a normally leak-tight, but releasable, communicative engagement. The invention further consists in the parts and combinations and arrangements of parts 40 hereinafter described and claimed.

In the accompanying drawing illustrating a practical embodiment of the invention,—

Figure 1 is a view in side elevation, showing the extinguisher in place on the supporting bracket;

Fig. 2 is a view in front elevation, of the bracket with the extinguisher removed, the pipe coupling being shown in section;

Fig. 3 is a top plan view of the bracket;

Fig. 4 is a fragmentary view of the discharge end portion of the extinguisher; and

Fig. 5 is a view illustrating the invention as applied to an aeroplane or automobile.

Referring now to the drawing, the number 55 1 designates the body shell or barrel

of an ordinary hand fire extinguisher whose end portions 2 and 3 are respectively convexed or crowned.

At the discharge end of the extinguisher is a nipple or nozzle 4, while at the opposite 60 end is the usual operating handle 5, the stem 6 of which latter extends into the barrel 1 and carries or controls the discharge valve and other internal parts or devices (not shown) for the control and operation of the 65 extinguisher.

The particular construction and operation of the extinguisher, of itself, constitutes no part of the present invention, except in the general combination and arrangement as 70 hereinafter set forth and claimed. Hence, no further detailed description thereof is deemed necessary in this specification.

The present invention, as hereinbefore pointed out, comprehends a novel supporting device or bracket. As shown, it comprises a body member, preferably an elongated, flat plate or bar 7, which is apertured, as at 8, for the reception of securing screws or bolts, or, obviously, it may be 80 otherwise suitably provided or arranged for attachment to the body of the vehicle, preferably within the cowl, in convenient reach of the operator.

At one end of the member 7 is a concavo-convex plate or support 9 for the reception of the nozzle end of the extinguisher, while at the opposite end of said member 7 is a similar plate 10 for engaging the handle end of the extinguisher, but differing, however, in that the first mentioned plate is preferably rigid, while the latter is resilient or yieldably supported, but with sufficient strength to normally hold the extinguisher in place and yet permit it to be readily 95 placed in position and removed, at will, when occasion requires. However, no set design or structure may be followed in this respect, as considerable modification is within the contemplation of the invention, 100 according to the particular construction of the extinguisher to be used, it being understood that the invention broadly comprehends any resilient or yieldable clamping or retaining device.

The two plates 9 and 10, as shown, have tongue portions or extensions 11, 12, respectively, which are turned so as to be fastened to the body member 7, as by rivets 13, 14.

As an additional retaining means, the 110

body member 7 may have a supplemental spring clip 15 attached thereto intermediate its end portions, as at 16, so that the two opposed curved arms of the clip may clamp 5 the barrel 1.

To make clearance for the stem 6 of the operating handle 5 so as to permit free manipulation thereof while the extinguisher is in place, and also to facilitate the placing of 10 the extinguisher on, and its removal from, the bracket, the plate 10 is provided with a diametrical slot 17 extending from its middle to the margin, as shown more clearly in Figs. 2 and 3. In this way the extinguisher 15 may be readily placed and removed by tilting it on the plate 9 and moving it so as to spring the plate 10, the stem 6 moving into and out of the slot 17, said plate 10 pressing on the end of the extinguisher to 20 hold the latter in place and moving back to normal position when the same is removed.

The supporting plate 9 is provided with an axially bored nipple or coupling extension 18, which may be screw-threaded, as 25 shown, or otherwise provided for the attachment of a coupling 19 on a suitable pipe 20 having a nozzle 21. The plate 9 is further provided with a socket 22 to receive the nozzle 4 of the extinguisher and communicating with the bore in the coupling extension 18. Obviously, this socket may be of suitable metal and ground to afford a releasable, but leak-tight, fit with the nozzle 4, or it may be provided with a gasket or 30 seat of material such as pressed fiber or rubber.

To hold the operating handle 5 in normal position and guard against accidental displacement thereof it is preferable to provide 40 a suitable catch or latching device therefor on the holder. As shown in the drawings this device comprises a substantially Z-shaped member 23 of suitable spring metal, one arm of which is hinged to the supporting plate 7, as at 24, and the other arm projecting normally upward and having an aperture 25 to receive the end portion of said handle 5 (see Fig. 1). The 45 spring tension of this member 23 need be only slight so that it may hold in place and yet be readily sprung from engagement with said handle member 5 and swung on its pivot 24 out of the way when it is desired to operate the extinguisher.

55 A practical application of the invention to an aeroplane or automobile is illustrated in Fig. 5 wherein the numeral 26 designates the body portion of the vehicle in the region of the driver's seat. In this instance the supporting bracket is mounted on the dash 60 board 27 in front and within easy reach of the driver as are the usual other devices provided for the operation and control of the vehicle. The pipe 20 is extended into the 65 engine compartment where the nozzle 21 is

suitably mounted so as to direct its discharge upon the carburetor, at which place fires more frequently occur. It is to be understood, however, that the discharge nozzle may be mounted in or on any other 70 part of the vehicle so as to be in the pre-trained position at any place where a fire is liable to occur and which is not conveniently accessible to the driver. By this arrangement, whereby the extinguisher may 75 be operated without being detached from the supporting bracket, the nozzle 21 at the end of the conducting pipe 20 is always in position to direct the extinguishing agent to the fire, with successful result, in a place 80 heretofore considered rather inconvenient and inaccessible for the use of a hand extinguisher in the usual way, and this without necessitating the operator leaving his regular controlling position in the car, or at 85 least not compelling him to assume an unduly hazardous position or cause him to lose control of the machine. This is particularly advantageous in the case of an aeroplane in flight, wherein the hazard of fire is 90 great and the extinguisher has been found practically ineffective when used in the heretofore customary manner, due to the time lost in disengaging the extinguisher from its holder and getting it ready for operation, and then the difficulty, and sometimes impossibility, in directing the discharge from the extinguisher to the fire from the operator's position in the car. 95

With the above noted advantages in the 100 use of the extinguisher while attached to the supporting bracket, there is the further advantage of its use in the ordinary way detached from the support.

Obviously, the device admits of considerable modification without departing from the spirit of the invention as defined by the appended claims. Therefore, it is not limited to the specific construction and arrangement shown in the drawing. 110

What is claimed is:

1. A supporting device having means for releasably holding a hand fire extinguisher thereon, a conducting pipe attached to said device and having a discharge nozzle, and means for effecting a releasable communicative connection between the outlet of said extinguisher and said pipe. 115

2. A supporting device for hand fire extinguishers, the same having means for releasably holding the extinguisher thereon, a pipe coupling on said supporting device, and means for effecting releasable communication between said coupling and the outlet of said extinguisher. 120

3. A supporting bracket for hand fire extinguishers, the same having a member for supporting one end of the extinguisher, and a yieldable clamping member for engaging the opposite end of the extinguisher, said 125 130

first mentioned supporting member having a pipe connection for releasable communication with the outlet of the extinguisher.

4. The combination of a hand fire extinguisher, a device for detachably supporting said extinguisher, and a conducting pipe, said supporting device having means for effecting releasable communication between said conducting pipe and said extinguisher thereon.

5. The combination of a hand fire extinguisher having a discharge nozzle at one end and an operating handle at its other end, a supporting bracket having a rigid member for receiving the discharge end of said extinguisher, said supporting member having a socket for the reception of the discharge nozzle releasably but with leak-tight effect, a conducting pipe attached to said supporting member and communicating with said socket, and a yieldable clamping member for releasably engaging the handle end of said extinguisher but free of the handle.

6. A supporting bracket for hand fire extinguishers, the same comprising a body

member, supporting members thereon for releasably engaging the ends of the extinguisher, a spring clip on said body member for releasably engaging said extinguisher laterally, a conducting pipe connected to said bracket, and means for effecting a releasable communicative connection between said pipe and the outlet of the extinguisher.

7. In a fire extinguishing equipment for automotive vehicles, a device constructed according to claim 1 and mounted accessibly of the driver's station, and the nozzle of the conducting pipe being mounted in pre-trained position at a possible source of fire remote from the driver's station.

8. In a fire extinguishing equipment for automotive vehicles, a device constructed according to claim 1 and mounted accessibly of the driver's station, and the nozzle of the conducting pipe being mounted in pre-trained position with respect to the carburetor.

In testimony whereof, I have hereunto set my hand.

DAVID B. SMITH.
